United States Patent Office

Des. 215,294
Patented Sept. 23, 1969

215,294

HOUSING FOR ELECTRONIC APPARATUS

Robert E. Kalvitis, Fairport, N.Y., assignor to Xerox Corporation, Rochester, N.Y., a corporation of New York

Filed May 9, 1968, Ser. No. 11,859

Term of patent 14 years

Int. Cl. D14—99

U.S. Cl. D26—5

FIG. 2

FIG. 3

FIG. 4

FIG. 5

FIG. 6

FIG. 7

FIG. 8

FIG. 9

FIG. 10

FIGURE 1 is a left-hand front perspective view of a first embodiment of a housing for electronic apparatus, showing my new design.

FIGURE 2 is a top plan view of said first embodiment.

FIGURE 3 is a side elevational view of said first embodiment.

FIGURE 4 is a rear elevational view of said first embodiment.

FIGURE 5 is a front elevational view of said first embodiment.

FIGURE 6 is a left-hand front perspective view of a second embodiment of a housing for electronic apparatus, showing my new design.

FIGURE 7 is a top plan view of said second embodiment.

FIGURE 8 is a side elevational view of said second embodiment.

FIGURE 9 is a rear elevational view of said second embodiment.

FIGURE 10 is a front elevational view of said second embodiment.

I claim:

The ornamental design for a housing for electronic apparatus, as shown and described.
